UNITED STATES PATENT OFFICE

JOSEPH GRANAT, OF SAN FRANCISCO, CALIFORNIA

DESIGN FOR A WEDDING RING

Application filed May 16, 1930. Serial No. 35,667. Term of patent 7 years.

To all whom it may concern:

Be it known that I, JOSEPH GRANAT, a citizen of the United States of America, residing at San Francisco, in the county of San Francisco and State of California, have invented a new, original, and ornamental Design for Wedding Rings, of which the following is a specification, reference being had to the accompanying drawing, forming a part thereof, the design on both sides of the ring being the same.

The figure shows a perspective view of my finger ring design.

I claim:

The ornamental design for a wedding ring substantially as shown and described.

JOSEPH GRANAT.
